ALARM MECHANISM FOR HANDBAGS OR
THE LIKE

Cyril Ernest Lewis, Eastwood, near Sydney, New South Wales, Australia, assignor of one-half to Duke Etherington, Sydney, New South Wales, Australia

Application August 27, 1936, Serial No. 98,252
In Australia August 27, 1935

4 Claims. (Cl. 200—157)

This invention relates to portable containers (such as handbags, attaché cases and the like) that are provided with audible alarm mechanism, adapted to automatically sound when the container is unauthorisedly removed from a bag's custodian or from a certain location.

Heretofore several mechanisms have been devised to operate an audible alarm within a bag, but such mechanisms are open to objection in that they are more or less complicated, and have required many working parts such as electrical relays or electromagnets and the like, which in addition to greatly adding to the dead weight of the bag seriously restrict the bag's capacity.

This invention has been devised to provide handbag alarm operating means wherein the mentioned defects are eliminated and which is characterised by extreme simplicity, compactness and lightness of construction.

According to this invention the alarm operating mechanism consists of an operating lever having a medial fulcrum on or adjacent one of the inner wall faces of the bag, one arm of this lever lies exteriorly of the bag and the other arm, inside the bag, is fashioned as a trigger adapted to contact with a switch lever in the bag, a spring (or springs) is provided which at all times tends to move the trigger and switch lever to "on" position.

This switch lever is situated within the bag and may be positioned to render the alarm mechanism non-operative, it constitutes part of a series circuit composed of an electrical battery and a sounding device.

In order that this invention may be readily carried into practical effect it will now be described with reference to the drawing (which is partly diagrammatic) wherein Fig. 1 is a side elevation of the alarm operating mechanism positioned in a bag (fragmentarily depicted).

Fig. 2 is an end elevation of Fig. 1 with the major part of the bag omitted.

Fig. 3, 4 and 5 are respectively side elevation, end elevation and plan of the mechanism with cover removed.

The bag 6 has handle 7 angle frame 8 and ordinary locking means (not shown). The alarm mechanism has an operating lever 9 having one arm 10 shaped and juxtaposed the handle 7 as shown, the fulcrum 11 of lever 9 passes through the bag frame 8 and a base plate 12, interiorly of the bag is one arm 13 of lever 9, this arm 13 constitutes a trigger having a slot 14 for one end 15 of a helical spring 16 wound about a post 17 fast in the base plate 12. This base plate is secured

to the frame 8 by screws 18 which are of extended length and which together with the post 11 constitute affixing means for a cover plate 19.

Affixed to plate 12 is a fulcrum post 20 upon which is mounted a switch lever 21. This switch lever has a hand piece 22 adapted to protrude through the floor of the cover plate 19, a contact arm 23, a slotted lug 24 for the end 25 of spring 16 and a tooth or dog 26 which normally rests in contact with the arm 13 of lever 9. The fulcrum post 20 constitutes a terminal for a lead 27 and its companion lead 28 has terminal 29 provided with a head 30 adapted to be contacted by the arm 23. Adjacent the hand piece 22 the base plate 12 has an integral wedge 31 upon which the said hand piece jams when it is desired to render the mechanism inoperative. The leads 27 and 28 form a circuit which includes a battery and electrical sounding device which are contained in the bag 6 as indicated diagrammatically at 32 and 33 respectively.

In use the levers 9 and 21 are positioned as shown in the drawing and the lever arm 10 is held close against the handle 7. When the hand grip is relinquished the spring 16 causes the lever arm 10 to fall thus removing the arm 13 from the dog 26, this enables the spring 16 to effect descent of the switch arm 23 which on abutting the terminal head 30 closes the circuit and the alarm is sounded. Whilst sounding, the dog 26 is beyond the reach of lever arm 13 so that to silence the alarm it is ineffectual to manipulate lever arm 10 and it is thus necessary to open the bag and gain access to the hand piece 22. To render the alarm inoperative the hand piece 22 is travelled towards the wedge 31 until it firmly jams thereagainst.

It will be seen that by suitably modifying lever arm 10 it could protrude through the floor of the bag in order to sound the alarm when the bag is lifted clear of its support.

I claim:

1. In an electrically operated alarm device for handbags and the like, a circuit-making and breaking mechanism actuated by releasing the grip on the handle of a handbag, comprising a circuit-controlling member pivoted within the handbag, means urging said member to circuit-closing position, and a latching member pivoted within the handbag for maintaining said circuit-controlling member in circuit-opening position against the action of said last-mentioned means, said latching member having a portion extending exteriorly of the handbag in cooperative relation with the handle thereof, so that said portion may

be grasped together with the handle to hold said latching member in latching position.

2. In an electrically operated alarm device for handbags and the like, a circuit-making and breaking mechanism actuated by releasing the grip on the handle of a handbag, comprising a small casing within the handbag, a diminutive circuit-controlling member pivoted within said casing, means urging said member to circuit-closing position, a latching member having a portion pivoted within said casing for maintaining said circuit-controlling member in circuit-opening position against the action of said last-mentioned means, said latching member having an other portion extending exteriorly of the handbag in cooperative relation with the handle thereof, so that said last-mentioned portion may be grasped together with the handle to hold said latching member in latching position, and means on said circuit-controlling member extending outside said casing for returning such member manually to circuit-opening position after circuit-closing actuation of the mechanism.

3. In an electrically operated alarm device for handbags and the like, a circuit-making and breaking mechanism actuated by releasing the grip on the handle of a handbag, comprising a circuit-controlling member pivoted within the handbag, means urging said member to circuit-closing position, a latching member pivoted within the handbag for maintaining said circuit-controlling member in circuit-opening position against the action of said last-mentioned

means, said latching member having a portion extending exteriorly of the handbag in cooperative relation with the handle thereof, so that said portion may be grasped together with the handle to hold said latching member in latching position, means on said circuit-controlling member for returning it manually to circuit-opening position after circuit-closing actuation of the mechanism, and latch means arranged cooperatively with said last means for rendering said circuit-controlling member inoperative at will.

4. In an alarm device for handbags and the like, circuit-making and breaking means actuated by releasing the grip on the handle of a handbag, comprising a lever fulcrumed in said handbag having an arm shaped complementary with the handle of said handbag and positioned in juxtaposition thereto, a switch lever fulcrumed in said handbag having an arm constituting an electrical switch contact and another arm constituting a manipulative handle, a projection on said first lever, a trip dog on said switch lever engageable by said projection to hold the switch lever in circuit-opening position, a spring constructed and arranged to actuate said levers to release said trip dog and to move said switch lever to circuit-closing position when the arm of said first lever is released, and means arranged cooperatively with said other arm to latch said switch lever in inoperative position.

CYRIL ERNEST LEWIS.
